WINDOW REGULATOR CONSTRUCTION

William C. Devereaux, Detroit, Mich.

Application January 29, 1940, Serial No. 316,250

5 Claims. (Cl. 263—126)

This invention relates generally to window regulators for sliding closures and refers more particularly to improvements in the means for operatively connecting the window regulator arm to a slidable closure.

In motor vehicle body constructions, it is customary to provide a horizontal guide at the bottom of the closure and to provide a stud on the free end of the regulator arm extending through an elongated slot in the guide so that swinging the free end of the arm in opposite directions respectively raises and lowers the closure. In accordance with conventional practice, the stud is provided with a head engageable with one side of the guide bracket and a spring pressed washer is slidably mounted on the stud for frictional engagement with the opposite side of the guide bracket. The spring acting on the washer must be sufficiently strong to prevent rattling of the parts and, as a result, considerable friction is introduced in the assembly. This friction is objectionable because it increases the resistance to sliding movement of the closure by the regulator arm and renders the operation of the regulator more difficult.

It is one of the principal objects of this invention to increase the ease of operation of a window regulator of the above general type to raise or lower a closure by reducing the friction between the upper end of the regulator arm and horizontal guide to a minimum. In accordance with this invention, the free end of the regulator arm is insulated from metallic contact with the guide by a material having a relatively low coefficient of friction. As a result, the resistance to sliding movement of the regulator arm stud in the guide bracket is not only reduced to a minimum, but more quiet operation is insured.

With the foregoing, as well as other objects in view, the invention resides in the novel construction of the connection between the free end of the regulator arm and horizontal guide. This construction will be made more apparent as this description proceeds, especially when considered in connection with the accompanying drawing, wherein:

Figure 1 is a semi-diagrammatic elevational view showing a typical regulator arm connected to a closure in accordance with the present invention;

Figure 2 is an enlarged sectional view taken substantially on the plane indicated by the line 2—2 of Figure 1;

Figure 3 is an elevational view of a part of the connection shown in Figure 2.

Referring now more in detail to the several figures of the drawing, it will be noted that the reference character 10 designates a vertically slidable closure in the form of a glass panel having a retaining channel 11 secured to the bottom edge thereof. Positioned directly beneath the glass retaining channel 11 is a channel-shaped guide bracket 12 having the base portion 13 extending vertically and having the upper flange 14 secured to the base of the glass retaining channel 11 for movement as a unit with the closure 10. Upon reference to Figure 2, it will be noted that the base 13 of the guide bracket is formed with an elongated slot 15 therethrough having flanges 16 projecting laterally from the opposed longitudinal edges of the slot. The flanges 16 are flared outwardly with respect to the longitudinal center line of the slot and form vertically spaced guide surfaces 17.

The width of the slot 15 is sufficient to receive a stud 18 having a reduced portion 19 at the inner end riveted or otherwise fixedly secured to the free end of a regulator arm 20 and having a cylindrical portion 21 intermediate the ends adapted to ride in the slot 15. The outer end of the stud is provided with a frusto-conically shaped head portion 22 integrally connected to the cylindrical portion 21 by means of a reduced neck portion 23 and having the end of maximum diameter positioned adjacent the cylindrical portion 21. The arrangement is such as to provide an annular recess 24 on the stud 20 between the head 22 and the cylindrical portion 21.

Referring again to Figure 2 of the drawing, it will be noted that the inner side of the base 13 of the guide bracket is engaged by a disc 25 formed of a non-metallic material having a relatively low coefficient of friction. Although various different types of composition material may be employed to form the disc 25, nevertheless, I prefer to fashion the same from a lubricant impregnated leather since I have found that this material may be slid along the metal surface of the base 13 of the bracket with the minimum friction. The disc 25 has a backing in the form of a metal disc 26 dished in a direction away from the base 13 on the guide bracket 12 and slidably mounted on the reduced portion 19 of the stud. The reduced portion 19 of the stud forms an annular shoulder 27 at the inner end of the cylindrical portion 21 and both discs are normally yieldably urged in a direction toward

the shoulder 27 by means of a suitable coil spring 28. The coil spring 28 surrounds the reduced portion 19 of the stud with the opposite ends respectively abutting the free end of the regulator arm 20 and the metal disc 26. The non-metallic disc 25 is highly flexible so as to conform to the contour of the dished disc 26 and the portions of the base 13 on the bracket at opposite sides of the slot 15 are shaped to provide the minimum area of contact with the disc 25.

It will, of course, be understood that the maximum diameter of the stud 18 is less than the width of the slot 15 in order to permit the stud to be extended through the slot during assembly. In the present instance, the stud is maintained in assembled relation with the guide bracket 12 by means of a retainer 29. The retainer 29 is adapted to be snapped over the head 22 on the outer end of the stud into engagement with the adjacent end of the cylindrical portion 21 on the stud and slidably engages the guide surfaces 17 on the flanges 16 under the influence of the spring 28. In detail, the retainer 29 comprises a disc 30 having the central portion upset or bent axially inwardly with respect to the peripheral portion to form an annular conically-shaped portion 31 and having an opening 32 through the center of greater diameter than the cylindrical portion 21 of the stud so as to receive the outer end of the cylindrical portion. A non-metallic disc 33 is placed on the inner side of the disc 30 and this disc possesses sufficient flexibility to conform to the shape of the disc 30. The disc 33 is also centrally apertured to receive the outer end of the cylindrical portion 21 on the stud and is preferably formed of the same material as the disc 25. The annular portion 34 of the disc 33 engages the longitudinal guiding surfaces 17 on the flanges 16 and, under the influence of the spring 28, cooperates with the non-metallic disc 25 to yieldably grip the guide bracket 12 therebetween. Inasmuch as both the disc 25 and the disc 33 are formed of a material having a low coefficient of friction, it necessarily follows that the minimum resistance is offered to sliding movement of the stud longitudinally of the guide bracket. Also, in view of the fact that both the disc 33 and disc 25 are formed of non-metallic material, it follows that the connection will be quiet in operation.

The discs 30 and 33 are held on the stud by means of a spring metal disc 35 having a continuous peripheral portion abutting the outer side of the peripheral portion of the disc 30 and having a spoked central portion. The radially inner ends of the spokes are free from connection with each other and form flexible fingers 36 of a length predetermined to permit the same to be snapped over the head 22 on the stud into the annular recess 24. The peripheral portions of the three discs 30, 33 and 35 are held in permanent assembled relationship by means of a sheet metal ring 37 crimped over the peripheral portions of the discs 33 and 35.

It will be noted from the foregoing that the non-metallic disc 13 forms a unit with the retainer and is assembled on the stud in a position to engage the guide surfaces 17 on the flanges 16 by merely snapping the retainer over the head 22 on the outer end of the stud. The flexible disc 25 may, of course, be assembled on the reduced portion 19 of the stud as a unit with the backing disc 26 and spring 28 prior to securing the stud to the regulator arm. It follows, therefore, that the construction is rela-

tively simple and lends itself to ease in assembly.

In accordance with conventional practice, the regulator arm 20 is connected to the usual gear segment 38 and the latter is rocked to effect the desired swinging movement of the arm by means of a pinion 39. The pinion shaft is operatively connected to a handle of usual construction positioned at the inner side of the vehicle for convenient manipulation.

What I claim as my invention is:

1. In a window regulator for a vertically slideable closure having a guide bracket at the bottom edge formed with an elongated slot therethrough, a regulator arm mounted for swinging movement and having a stud at the swinging end projecting laterally from the arm through said slot, a spring metal disc having a snap-on engagement with the free end portion of the stud to secure the stud in assembled relation with the guide bracket, a non-metallic disc formed of a material having a relatively low coefficient of friction positioned between the spring metal disc and adjacent side of the guide bracket for frictional engagement with said bracket, and means for securing said discs together as a unit.
2. In a window regulator for a vertically slideable closure having a guide bracket at the bottom edge formed with an elongated slot therethrough, a regulator arm mounted for swinging movement and having a stud at the swinging end projecting laterally from the arm through said slot, a spring metal disc having a snap-on engagement with the free end portion of the stud and having a diameter greater than the width of the slot through the guide bracket, a flexible non-metallic disc formed of a material having a relatively low coefficient of friction positioned between the spring metal disc and adjacent side of the guide bracket for frictional engagement with said guide bracket, a metal backing disc for the non-metallic disc positioned between the latter disc and said spring metal disc, and a ring crimped over the peripheral portions of said discs to secure the same together as a unit.
3. In a window regulator for a vertically slideable closure having a guide bracket at the bottom edge formed with an elongated slot therethrough, a regulator arm mounted for swinging movement, a stud projecting laterally from the swinging end of the regulator arm through said slot and having a head providing a shoulder, a metal disc having a plurality of radially inwardly extending spring fingers defining a central opening through the disc and possessing sufficient flexibility to spring over the head on the stud into engagement with said shoulder to hold the metal disc in assembled relation with the stud, a non-metallic disc carried by the metal disc and slidably engageable with the adjacent side of the guide bracket, and spring means acting through the head on said stud for urging the non-metallic disc into engagement with the guide bracket.
4. In a window regulator for a vertically slideable closure having a guide bracket at the bottom edge formed with an elongated slot therethrough, a regulator arm mounted for swinging movement, a stud projecting laterally from the swinging end of the regulator arm through said slot and having a head providing a shoulder, a metal disc centrally apertured to receive the stud and having a diameter greater than the width of the slot in the guide bracket, a non-metallic disc positioned between the metal disc and the adjacent surface of the guide bracket, a second disc having a plurality of spring fingers adapted

to spring over the head on the stud and snap into engagement with said shoulder, means for securing said discs together to form a unitary construction, and spring means for urging the discs toward the guide bracket to engage the non-metallic disc with said guide bracket.

5. In a window regulator for a vertically slideable closure having a guide bracket at the bottom edge formed with an elongated slot there-through, a regulator arm mounted for swinging movement and having a part extending laterally from the swinging end thereof through the slot in the guide bracket, an angular shoulder on said part adjacent the free end of the latter, an inwardly bowed disc centrally apertured to

receive the free end portion of the part aforesaid, an outwardly bowed disc centrally apertured to receive the free end of said part and engageable with said shoulder, the peripheral portions of the discs being secured together to form a unit, a nonmetallic disc having a relatively low coefficient of friction positioned against the inner surface of the inwardly bowed disc and having the periphery thereof secured to the peripheral portions of both the aforesaid discs, and means for holding the two first mentioned discs under tension between the shoulder on said part and the adjacent side of the guide bracket

15
